UNITED STATES PATENT OFFICE.

FRANK HAETTEL, OF COLUMBUS, OHIO.

DESIGN FOR A SIGN-LETTER.

SPECIFICATION forming part of Design No. 28,955, dated June 28, 1898.

Application filed March 5, 1898. Serial No. 672,781. Term of patent 14 years.

To all whom it may concern:

Be it known that I, FRANK HAETTEL, a citizen of the United States, residing at Columbus, in the county of Franklin and State of Ohio, have invented and produced a new and original Design for Sign-Letters, of which the following is a specification, reference being had to the accompanying drawings, forming part thereof.

Referring to the drawings, Figure 1 is a face view of a sign-letter containing my design, and Fig. 2 is a transverse section of the same on line $y y$ of Fig. 1.

The leading feature of my design consists in the raised marginal portions which follow the outer and inner outline of the letter, the raised margin thus formed consisting of inner and outer parallel portions which are raised

above the body of the letter and the outer marginal portion being raised above the inner 20 marginal portion.

a represents the body of the letter, which is of the open or outline form.

c represents the outer and higher marginal portions, and *d* represents the inner marginal 25 portions.

Having described my invention, what I claim as new, and desire to secure by Letters Patent, is—

The design for a sign-letter, substantially 30 as herein shown and described.

FRANK HAETTEL.
